UNITED STATES PATENT OFFICE.

MATTHIAS HOHNER, OF TROSSINGEN, GERMANY, ASSIGNOR TO HANS HOHNER, OF NEW YORK, N. Y.

DESIGN FOR A HARMONICA.

No. 39,410.

Specification for Design.

Patented July 7, 1908.

Application filed January 2, 1908. Serial No. 409,103. Term of patent 3½ years.

To all whom it may concern:

Be it known that I, MATTHIAS HOHNER, a citizen of Germany, residing at Trossingen, Germany, have invented a new, original, and ornamental design for Harmonicas, of which the following is a specification, reference being had to the accompanying drawing, forming part thereof.

The figure is a perspective view of a harmonica, showing my new design.

I claim:

The ornamental design for a harmonica, as shown.

MATTHIAS HOHNER.
